UNITED STATES PATENT OFFICE.

EDWARD OSBORN AND JAMES J. NOLAN, OF ALBANY, NEW YORK.

SOUND-ABSORBING DEVICE.

1,171,683.

Specification of Letters Patent. Patented Feb. 15, 1916.

Application filed February 12, 1915. Serial No. 8,017.

To all whom it may concern:

Be it known that we, EDWARD OSBORN and JAMES J. NOLAN, citizens of the United States of America, residing at Albany, in the county of Albany and State of New York, have invented new and useful Improvements in Sound-Absorbing Devices, of which the following is a specification.

This invention relates to improvements in sound absorbing devices for telephone transmitters.

Any noise, (other than words spoken) in the vicinity of the telephone set, that enters the transmitter causes a rumble and not only travels to the receiving end of the line, but also reverts to the receiver of the telephone set in the vicinity of the noise, thereby impairing the hearing of the party at the telephone set in the zone of the noise. In other words, all noise near a telephone set enters the transmitter and reverts to the receiver causing a rumble in the receiver which prevents the party using the telephone from hearing distinctly; and it is not the receiver nor the idle ear which catches the foreign sounds.

Therefore, in carrying out the present invention, it is our purpose to provide a sound absorbing device for the transmitters of telephone instruments whereby sounds other than those spoken or otherwise sent directly into the mouth piece of the transmitter will be excluded from the transmitter diaphragm and absorbed previous to entering the mouth piece so that the party at the telephone equipped with the sound absorbing device will be enabled to hear clearly and distinctly irrespective of any noise in the vicinity of such telephone set, and the party at the other end of the line enabled to hear clearly irrespective of any noises in the vicinity of the telephone set equipped with the sound absorbing device.

It is also our purpose to provide a device of the class described which may be readily and quickly applied to any telephone transmitter so as to exclude noises therefrom and which will embrace the desired features of simplicity, efficiency and durability and which may be manufactured at comparatively small cost.

With the above and other objects in view,

the invention consists in the construction, combination and arrangement of parts hereinafter set forth in and falling within the scope of the claims.

In the accompanying drawing; Figure 1 is a view in side elevation of a telephone transmitter equipped with a sound absorbing device constructed in accordance with the present invention. Fig. 2 is a sectional view through the device and transmitter. Fig. 3 is a perspective view of the device removed from the transmitter.

Referring now to the drawing in detail, 1 designates the transmitter of a telephone instrument or set, such transmitter being of any suitable or well known construction and provided with the usual mouth piece 2.

3 indicates our improved sound absorbing device as an entirety and such device comprises a cup-shaped body 4 designed to fit over the mouth piece 2 of the transmitter and having the flange thereof surrounding the mouth piece concentrically of the latter and spaced apart therefrom. The end wall of the body 1 is formed centrally with an opening 5 of a diameter less than that of the mouth piece 2 and formed integral with the end wall of the body 4 concentrically of the opening 5 and projecting outwardly from such end wall is a supplemental mouth piece 6. The outer end of the mouth piece 6 is flared outwardly or bell shaped as at 7 and the inner portion of the mouth piece is of a diameter corresponding with that of the opening 5 and relatively small as compared with the diameter of the mouth piece 2. Secured to the inner surface of the end wall of the cup-shaped body 4 and extending across the opening 5 and the mouth piece 2 between the latter and the supplemental mouth piece is a diaphragm 8 which partially covers the mouth piece 2 and is constructed of suitable sound absorbing material such, for instance, as cloth and having the peripheral edge thereof suitably secured to the side wall or flange of the body 4.

In order to hold the sound absorbing device 3 to the mouth piece of the telephone transmitter any suitable means may be employed. In the present instance, a collar 9 surrounds the inner end portion of the

mouth piece 6 adjacent to the end wall of the cup and formed on the collar at diametrically opposite points and projecting outwardly therefrom are arms 10 having the outer ends thereof bent at right angles to themselves as at 11 and extending toward the telephone transmitter and formed with outwardly projecting lugs 12 adapted to engage similar lugs 13 formed on the 10 bent end portions 14 of arms 15 formed on a collar 16 surrounding the transmitter and extending outwardly from such collar at diametrically opposite points. The lugs 12 and 13 are provided with alining openings 15 and threaded into such openings are securing screws 17. By means of this construction, it will be seen that the sound absorbing device may be rigidly and securely fastened to the mouth piece of the telephone 20 transmitter. It is conceivable, however, that other fastening means may be employed.

From the foregoing description taken in connection with the accompanying drawing, the construction, mode of operation and 25 manner of employing our improved sound absorbing device will be readily apparent. It will be seen that we have provided a sound absorbing device whereby any noise in the vicinity of the transmitter will be 30 excluded from the latter and absorbed by the diaphragm 8, thereby preventing the transmission of such noise over the telephone line and enabling the party at the telephone set equipped with the sound absorbing device to hear clearly and distinctly 35 irrespective of any noise immediately in the vicinity of the telephone.

We are aware of the fact that heretofore it has been proposed to apply auxiliary, 40 or what may be termed supplemental, mouth pieces to the mouth pieces of telephone transmitters, but in transmitters of this type with which we are acquainted, this auxiliary or supplemental mouth piece is employed merely for the purpose of confining 45 the sound waves sent into the transmitter and preventing the escape of such waves from the transmitter so that a person in the vicinity of the telephone instrument 50 will be unable to hear what is said by the party using the telephone, and not as sound absorbing devices for preventing the entrance of foreign sounds into the transmitter. Furthermore, none of these sound 55 excluding devices, so far as we are aware, employs a sound absorbing diaphragm that is interposed between the two mouth pieces and that acts to absorb all sounds other than those sent directly into the transmitter; but these transmitters with which 60 we are acquainted have the walls thereof lined with material that prevents the escape of the sound waves through such walls. So far as we know, we are the first to employ 65 a sound absorbing diaphragm between

the mouth piece of the telephone transmitter and the supplemental or auxiliary mouth piece for the purpose of absorbing sound waves other than those sent directly into the mouth piece. Again, so far as we have been able to discover, we are the first to prevent foreign sounds at the sending end of a telephone set from entering the diaphragm and reverting to the receiver, by absorbing such foreign sounds previous 75 to the same impinging against the diaphragm of the transmitter. By our method and apparatus, we are enabled to prevent any noise in the vicinity of the telephone instrument from entering the transmitter 80 and reverting to the receiver.

While we have herein shown and described the preferred form of our invention by way of illustration, we wish it to be understood that we do not limit or confine 25 ourselves to the precise details of construction herein described and delineated, as modification and variation may be made within the scope of the claims without departing from the spirit of the invention. 90

We claim:

1. The combination with a telephone transmitter, of a supplemental mouth piece secured to the mouth piece of the transmitter, and a diaphragm of sound absorbing material interposed between said mouth pieces and partially covering the transmitter mouth piece to absorb sound waves other than those sent directly through the mouth piece. 100

2. The combination with a telephone transmitter, of a supplemental mouth piece secured to the mouth piece of the transmitter, and a cloth diaphragm interposed between said mouth pieces and partially covering the transmitter mouth piece to absorb sound waves other than those sent directly through the mouth piece. 105

3. The combination with a telephone transmitter, of a sound absorbing device 110 secured to the mouth piece of the transmitter and comprising a cup-shaped body disposed upon the outer end of the transmitter mouth piece and having the flange thereof surrounding the transmitter mouth 115 piece concentrically of such mouth piece and the end wall thereof formed with an opening alining with the opening in the mouth piece and of less diameter than that of the mouth piece, a supplemental mouth 120 piece secured to the end wall of said body, concentrically of the opening therein and projecting outwardly therefrom and a diaphragm of sound absorbing material interposed between the transmitter mouth piece 125 and the end wall of said body across the opening in the end wall of the body to absorb sound waves other than those sent directly through the mouth piece.

4. A sound absorbing device for telephone 130

transmitters comprising a two-part mouth piece secured to the transmitter, and a diaphragm of sound absorbing material interposed between said parts and partially closing the opening through said parts to absorb sound waves other than those sent directly through the mouth piece.

In testimony whereof we affix our signatures in presence of two witnesses.

EDWARD OSBORN.
JAMES J. NOLAN.
